Primary Examiner—Louis S. Zarfas*Assistant Examiner*—John Windmuller(74) *Attorney, Agent, or Firm*—Patterson, Thuente, Skaar & Christensen, P.A.(57) **CLAIM**

I claim the ornamental design for clip, as shown.

DESCRIPTION

FIG. 1 is a front perspective view of a clip showing my new design;

FIG. 2 is a left side elevational view thereof, shown attached to a different clip;

FIG. 3 is a front elevational view thereof;

FIG. 4 is a rear elevational view thereof;

FIG. 5 is a top plan view thereof; and,

FIG. 6 is a bottom plan view thereof.

The broken line showing of a different clip in FIG. 2 is for illustrative purposes only and forms no part of the claimed design.
